Des. 229,509
Patented Dec. 4, 1973

229,509

COMBINED RADIO RECEIVER, TAPE PLAYER, CLOCK AND TELEVISION RECEIVER

Kumi Yanagisawa, Fumiharu Ohta, Susumu Ezawa, and
Masaharu Katayama, Saigiyou, Japan, assignors to
Matsushita Electric Industrial Co., Ltd., Osaka, Japan

Filed Apr. 6, 1972, Ser. No. 241,885

Term of patent 14 years

Int. Cl. D14—03

U.S. Cl. D56—4 D

FIG. 1

FIG. 2

FIG. 3

FIG. 4

FIG. 5

FIG. 1 is a front perspective view of a combined radio receiver, tape player, clock and television receiver showing our new design,

FIG. 2 is a right side perspective view,

FIG. 3 is a rear elevational view,

FIG. 4 is a top plan view, and

FIG. 5 is a left side and bottom perspective view thereof.

We claim:

The ornamental design for a combined radio receiver, tape player, clock and television receiver, as shown.
